Filed Jan. 27, 1961, Ser. No. 63,723

Term of patent 14 years

(Cl. D58—17)

FIG.1

FIG.2

FIG.3

FIG. 1 is a perspective view of a food container or the like, showing my new design.

FIG. 2 is a side elevational view thereof, the opposite side being substantially the same;

FIG. 3 is a bottom plan view thereof;

FIG. 4 is an enlarged fragmentary view of a portion of FIG. 2.

The dominant features of my design reside in the portions shown in full lines.

I claim:

The ornamental design for a food container or the like, as shown and described.
